UNITED STATES PATENT OFFICE

145,328

DESIGN FOR A CIGARETTE LIGHTER OR SIMILAR ARTICLE

Nathan M. Robboy, Cleveland Heights, Ohio

Application October 16, 1945, Serial No. 122,892

Term of patent 7 years

(Cl. D48—27)

To all whom it may concern:

Be it known that I, Nathan M. Robboy, a citizen of the United States, residing in the city of Cleveland Heights, county of Cuyahoga, and State of Ohio, have invented a new, original, and ornamental Design for a Cigarette Lighter or Similar Article, of which the following is a specification, reference being had to the accompanying drawing, forming a part thereof.

Figure 1 is a side elevation of a cigarette lighter or similar article showing my new design;

I claim:

The ornamental design for a cigarette lighter or similar article, substantially as shown.

NATHAN M. ROBBOY.
